JOCKEY HELMET

John N. McMurry, Hawthorne, Calif.

Application September 13, 1956, Serial No. 42,915

Term of patent 14 years

(Cl. D3—13)

Fig. 1 is a side elevational view of a jockey helmet showing my new design;

Fig. 2 is a front elevational view; and

Fig. 3 is a rear elevational view thereof.

I claim:

The ornamental design for a jockey helmet, as shown.
